UNITED STATES PATENT OFFICE.

ALEXANDER EKLUND, OF ATTLEBORO, MASSACHUSETTS, ASSIGNOR, BY MESNE ASSIGNMENTS, TO J. F. STURDY'S SONS CO., A CORPORATION OF MASSACHUSETTS.

BRACELET-LINK.

1,215,920.

Specification of Letters Patent. Patented Feb. 13, 1917.

Application filed February 9, 1916. Serial No. 77,255.

To all whom it may concern:

Be it known that I, ALEXANDER EKLUND, a citizen of the United States, and resident of the city of Attleboro, in the county of 5 Bristol and State of Massachusetts, have invented certain new and useful Improvements in Bracelet-Links, of which the following is a specification.

This invention relates to bracelets of the 10 extension type, and the object of this invention is to provide a bracelet of this class comprising a plurality of compound links constructed of both guide members and slide members, and an attaching hook being 15 formed on the guide member of one or more of the links to facilitate their attachment to a watch or other ornament.

A further object of this invention is that the 20 guide link to which the hook is attached is also provided with a slide link like the rest of the links so as to lend to the bracelet the maximum amount of expansion.

A further object of the invention is the 25 forming of the hook portion from the stock of the bridge element and making the hook of double strength and stiffness by folding this stock over upon itself.

The invention further consists in forming 30 a hook on the guide links at opposite ends of the bracelet and connecting together the adjacent ends of two of the slide links.

The invention still further consists in the 35 provision of a spring tongue for closing the mouth of the hook, one end of said tongue being fixed to its link and its opposite end bent to extend into and be guided in the space between said guide link members.

With these and other objects in view, the 40 invention consists of certain novel features of construction, as will be more fully described, and particularly pointed out in the appended claims.

In the accompanying drawings:

Figure 1— is a side view of the complete 45 bracelet showing the end links as each being provided with a hook and attached to a watch.

Fig. 2— is an edge view showing the general arrangement of the interconnecting 50 links and illustrating the adjacent ends of two slide links as connected together by another link member.

Fig. 3— is a plan view showing one arrangement in which the two side members

of the guide link are connected together and 55 the hook portion as formed integral therewith.

Fig. 4— shows an edge view of the two side members of the guide link as bent into position and the stock at the end folded to 60 strengthen and stiffen the hook portion.

Fig. 5— is a side view of this hook link showing the hook member as bent into hook form also showing the spring tongue retaining fingers. 65

Fig. 6— is a view enlarged over that of Fig. 5 partly in section and showing the ends of the two fingers which serve to connect the spring tongue to this link.

Fig. 7— is a perspective view showing a 70 portion of the spring tongue with its recessed edges adapted to fit over the ends of the engaging fingers shown in Fig. 6.

Fig. 8— is a perspective view of the spring 75 tongue.

Fig. 9— is a sectional view showing one of the link members removed with the hook portion in section, and the spring tongue in section and attached to the link at one end, 80 its opposite end closing the mouth or opening into the hook and extending into the space between its members, also showing the slide link as slightly extended therefrom.

Fig. 10— is an edge view showing a portion of the hook link and a portion of the 85 spring tongue secured to the link by folding the retaining fingers over the same.

Referring to the drawings 12 designates the two end links in the bracelet 13, each of which links is provided with a hook shaped 90 member 14 whereby the bracelet ends may be readily attached to a watch 15 or other ornament.

The primary object of this invention is 95 the provision of a guide link to which is attached the hook member 14, said guide link being so constructed as to also permit a slide link 16 to work in the space between its side members 17. These side members may be formed in any suitable way and connected 100 together at their ends by any suitable form of bridge members 20. In this particular instance, however, I have provided an integral portion of the stock as at 19 serving as a bridge element for connecting together 105 one end of the side members. This integral stock extends forwardly as at 18 and is of a length sufficient to be bent into the form of

the hook member 14. Each of the other bridge members at the opposite ends of the side members is provided with suitable lips 21, which are adapted to fold about the inner connecting bar 22, see Fig. 6, by which construction the free ends of these link members are rigidly secured together in the manner fully illustrated in my Patent No. 1,166,821. When these side members as illustrated in Fig. 3, are folded over upon each other as illustrated in Fig. 4, the opposite edges 23 of the stock of this hook portion 18 are also folded over to abut against each other as shown in this figure, thus greatly stiffening and strengthening the hook which is then formed by bending the same around into the position illustrated in Figs. 5 and 9.

It is found in practice necessary to provide a spring tongue for closing the mouth 20 or opening of the hook to prevent the link from becoming accidentally unhooked. To accomplish this in a simple and effective way, I have provided a spring tongue 25 which is provided at one end with dovetail shaped notches 26 into which are fitted correspondingly shaped fingers 27 which fingers are formed integral with and are arranged to stand outwardly from the edges of the side members of this link as illustrated in Fig. 6. The end of this spring with its notches are then fitted over the fingers 27 and these fingers are folded over the end of the spring in the manner illustrated in Fig. 10 thereby securely binding 30 this end of the spring in position. The opposite end 28 of this spring is bent outward and upward in somewhat of a hook form and its extremity extends into the space 29 between the members of the guide link 40 whereby this free end is guided laterally and prevented from being bent to one side, and whereby this tongue may be pressed inwardly to open the hook after which this tongue is released to spring open to close 45 the hook, thus preventing accidental disengagement of the hook.

A feature of this construction is that the spring tongue 25 is attached to the inner edge of the link, but as these end links are 50 both attached to the watch their hook ends are raised slightly above the inner surface of the watch and this spring tongue is thus lifted or raised so that it does not rest upon the wrist of the wearer with sufficient pressure to open the hook.

The guide links are connected to the opposite ends of the bracelet and are provided with hooks by which they may be attached to a watch or the like, and each of these 60 hook links is provided with a slide link. It is found that somewhere in the bracelet either two guide links, or two slide links, must be connected together instead of an alternate connection, as is usually the case. 65 Therefore I have found it to be of consider-

able advantage in my improved construction to connect together the adjacent ends of the slide links 16 by a separate and independent small link 30 such as that illustrated in Figs. 1 and 2 by which construction the maximum elongation or extending effect of the bracelet is obtained.

Another point in my special construction is that dovetailing the fingers 27 into the spring tongue 25 assists the bridge elements 75 in holding together the ends of the side members 17 of the guide links 12.

Having thus described one illustrative embodiment of my invention, I desire it to be understood that although specific terms are employed they are used in a generic and descriptive sense and not for the purpose of limitation, the scope of the invention being set forth in the following claims.

I claim:

1. In a bracelet, a guide link comprising two spaced apart side members between which another link is adapted to slide, said members being connected together by bridge elements, one of the bridge elements forming a rigid hook, and a spring tongue for closing the mouth of said hook.

2. In a bracelet, a guide link comprising two spaced apart side members between which another link is adapted to slide, said members being connected together by bridge elements, the bridge element on one end forming a rigid hook, and a spring tongue for closing the mouth of said hook, the free end of said spring being guided between 100 said members.

3. In a bracelet, a guide link comprising two spaced apart side members between which another link is adapted to slide, said members being connected together by bridge elements, having fingers formed integral therewith, a hook member on one end of said link, and a spring tongue for closing the mouth of said hook, one end of said tongue being secured to said side members 110 by said fingers.

4. In a bracelet, a guide link comprising two spaced apart side members connected together by bridge elements, a rigid hook member formed integral with one end of said link, and a spring tongue secured at one end to said members, its opposite end being bent to close the mouth of said hook and to enter and be guided in the space between said members.

5. In a bracelet, a guide link comprising two spaced apart members connected by bridge elements, a hook member connected to both side members and formed by folding inwardly both edges of the stock of 125 said members, and a spring tongue for closing the mouth of said hook.

6. In a bracelet, a guide link comprising two spaced apart side members between which another link is adapted to slide, said 130

members being connected together by bridge elements, a hook member on one end of said link, a spring tongue for closing the mouth of said hook, one end of said tongue being permanently interlocked with both of said spaced apart side members to form a rigid construction.

In testimony whereof I affix my signature in presence of two witnesses.

ALEXANDER EKLUND.
